UNITED STATES PATENT OFFICE.

EDWARD J. BRANDT, OF WATERTOWN, WISCONSIN, ASSIGNOR TO BRANDT AUTOMATIC CASHIER CO., OF WATERTOWN, WISCONSIN, A CORPORATION OF WISCONSIN.

COIN-PAYING MACHINE.

Application filed April 18, 1921, Serial No. 462,193. Renewed June 19, 1925.

The object of the present invention is to improve the general construction of the machine referred to and to extend its utility by the provision of means for effecting a greater number of change-making combinations. The invention, therefore, contemplates a machine wherein payment of amounts in change ranging from one cent to ninety-nine cents may be effected, the combinations essential to this being formed by relatively few parts and by an organization of the same which renders the machine simple and compact.

A further object of the invention is the provision of a coin paying machine the construction of which includes operating plates wholly devoid of projections or recesses and co-operating in such manner with combination-forming instrumentalities for the amounts to be paid as to insure positive accuracy in the combinations of change made. The relation of these co-operating elements affords freedom of movement of the parts without liability of derangement thereof, and the payment of the exact amounts which the several combinations are designed to produce is assured.

The invention contemplates other objects and advantages which will appear as the nature of the same is better understood, the invention consisting substantially in the novel construction, combination and arrangement of parts hereinafter fully described, illustrated in the accompanying drawings, and finally pointed out in the appended claims.

The form of the invention herein disclosed is regarded as a practical adaptation thereof, but it is to be considered from an illustrative standpoint and is therefore not to be taken in a restrictive or limiting sense.

In the drawings—

Figure 1 is a longitudinal sectional view of a coin paying machine constructed in accordance with the present invention.

Figure 2 is a transverse sectional view as on the line 2—2, Fig. 1.

Figure 3 is a sectional plan view, parts being broken away, as on the line 3—3, Fig. 1.

Figure 4 is a detail elevation of certain of the coin ejector operating instrumentalities illustrated in one of the positions of the throw thereof in the discharge of the coins.

Figure 5 is a fragmentary sectional plan

view, on an enlarged scale, illustrating the relation of the key stems to the guides thereof.

Referring now in detail to the accompanying drawings, the numeral 10 designates a supporting frame for sustaining the body of the herein described machine. This frame may be of any desired construction, and may be formed of any desired material. It sustains the body 11, and within said body 60 is housed the operative mechanism with the exception of the keys for producing the various combinations for which the machine is designed. The upper portion of the forward end of the body 11 is inclined, and detachably mounted thereon is a coin tray 12 having a plurality of coin receptacles or chutes 13 for receiving stacks of coins of various denominations. The construction of this tray has no special significance to the invention, and the same need be described no further. The chutes 13, however, are so arranged that the stacks of coins held thereby are disposed in the order of single pennies, double pennies, double pennies, nickels, 70 dimes, dimes, quarters and half dollars. This arbitrary arrangement lends itself most conveniently for the payments ranging from one to ninety-nine cents, for which payments the machine primarily is designed.

Associated with each of the coin receptacles or chutes 13 is a coin ejector 14. This is in the form of an elongated finger, the forward end of which is designed to work within a slot 15 located in the front wall of the body 11 and adjacent to the bottom thereof, the ejector 14 thus being positioned at the base of the receptacle or chute 13 and in position to engage the lowermost coin of the stack of that receptacle. The rear end of the ejector 14 is pivoted, as at 16, to an upwardly extending lug 17 formed on a slideable carrier 18. This carrier works in a slot formed in a transversely extending guide bar 19, said guide bar being supported on the bottom of the body 11, and said carrier has a longitudinally extending slot 20 in which is fitted an anti-friction roller 21 which is supported by the bar 19. The roller 21 sustains the weight of the carrier 18 and assists in the free movement thereof as the same is moved back and forth in the manner hereinafter described. At the forward end of the carrier 18 is located a supporting finger 22, and said finger has a re- 100 105 110

cess 23 the upper end of which receives a coil spring 24 of relatively weak strength, which coil spring surrounds a guide stud 25 carried by the ejector 14. The spring 24 serves to maintain the ejector 14 in contact with the upper end of the slot 15 in which it works, thus positioning the forward end of the ejector for assured engagement with the lowermost coin of the stack in the receptacle or chute 13.

Surrounding the carrier 18 is a coil spring 26. This spring is of sufficient strength normally to maintain the ejector 14 in retracted position, and also to move the ejector 14 to such position after the same has been operated for discharging a coin or coins from the receptacle 13. The forward end of the spring 26 abuts against the guide bar 19, while the rear end thereof engages a washer 27 located at the rear end of the carrier 18.

The roller 21 serves in a measure as a pivotal point for the forward end of the carrier 18 as the latter is actuated in connection with the discharge of the coins. But the rear end of said carrier is also pivotally connected to a hanger link 28, the upper end of said link 28 being pivotally mounted on a supporting rod 29 mounted in depending marginal flanges 30 of a supporting plate 31. The rear end of this plate is connected, as at 32, to the rear wall of the body 11, while the forward end thereof is connected to the upper ends of a plurality of supporting posts 33 which extend upwardly from the bottom of said body 11.

It will be understood that the construction thus far described with respect to the coin ejector 14, its carrier 18, the spring 26, which controls movement of said carrier, and the hanger link 28, is present in the machine as component elements of each of the coin chutes. Each group of these elements is designed for independent operation, and in order to accomplish this a rock shaft 34 is provided for each of the carriers 18. These shafts 34, as clearly illustrated in Fig. 3, are arranged in parallel relation, and extend transversely of the supporting plate 31. They are journaled in the depending flanges 30 of the supporting plate 31, and at each end of each of said shafts is located an outstanding angularly disposed crank arm 35. Depending from each of said rock shafts is a connecting arm 36 from the lower end of which extends a connecting link 37, said link being attached at its forward end to the rear end of the carrier 18 of the particular coin ejector 14 which the arm 36 is designed to operate.

The several rock shafts 34 are operatively related to a plurality of combination bars 38, the function of which is to effect the different combinations of change which the machine will produce. As illustrated in Fig. 2, where one of these bars 38 appears in

face elevation, each of the combination bars comprises a pair of tie rods 39 on the ends of which are mounted guide brackets 40. The guide brackets of each bar 38 fit within a pair of oppositely-positioned slots 41 formed in depending guide plates 42, and pivotally connected to the lower extremities of said guide brackets 40 are connecting links 43 which, in turn, are pivotally attached at their lower ends to the free extremities of the crank arms 35 formed at the ends of the rock shafts 34. One of the combination bars 38 is associated with each of said rock shafts 34, and through the medium of the latter, the depending connecting arm 36, and the links 43, the coin ejecting mechanism of one of the coin receptacles or chutes 13 is operated when said combination bar is operated.

Each combination bar 38 includes a plurality of contact fingers 44, which are mounted upon the tie rods 39 of said bar, and it is the arrangement of said contact fingers 44 on each of said bars 38 which determines the particular combinations of change to be paid out when the bar is operated. These contact fingers 44 are spaced apart in the desired relation by spacing blocks 45 also carried by the tie rods 39 and fitted between the contact fingers 44 to separate the latter to the required extent of spacing for the selective arrangement of the fingers 44 necessary for producing the various change combinations. As clearly shown in Fig. 2, the fingers 44 extend above the spacing blocks 45 to a substantial degree, and where the fingers are spaced apart there are notches or recesses of substantial depth therebetween.

For the purpose of operating the combination bars 38 a plurality of operating plates 46 is employed. These plates are formed of thin attenuated metal, and each is provided with an upwardly extending key stem 47 the upper end of which passes through a slot 48 in the top 49 of the body 11. At the upper end of each of the stems 47 is positioned a key 50, each of said keys bearing a symbol indicative of the particular amount of change to be paid out by the machine on the operation of that key. The lower ends of the stems 47 also pass through guide slots 51 formed in a horizontal guide plate 52, said guide plate being suitably supported in depending spaced relation to the top of the body 11. The guide plates 42 for the combination bars 38 are connected to this plate 52. Surrounding each of the key stems 47 is a coil spring 53, the lower ends of said springs bearing against the guide plate 52, while the upper ends thereof contact with suitable stops carried by the key stems. It will thus be seen that on depression of the keys 50 the springs 53 will be compressed, and the expansion of

said springs will return the keys to their normal position when pressure has been released therefrom. Due to the expansion of the springs 53, the operating plates 46 normally will exert no downward pressure on the combination bars 38, and such pressure is effected only by contact of the plates 46 with the fingers 44 of said bars. As also clearly seen in Fig. 2, the operating plates 46 extend over such of the contact fingers 44 as are selected for actuation in making particular combinations of change. The spacing of the fingers 44, as already previously indicated, is determined by the arrangement to be followed in producing the various combinations of change to be paid out. If, therefore, in producing these particular combinations contact of certain of the operating plates 46 with certain of the fingers 44 is to be avoided, the fingers will be so spaced apart that the notches or recesses therebetween will lie below the particular operating plates 46 which are intended to clear the fingers 44 when said plates are depressed.

To permit a limited degree of lateral movement to the plates 46, and thus insure contact of the same with the fingers 44, as well as freedom of movement with respect to each other, the slots 51 in the guide plate 52 are slightly wider than the thickness of the key stems 47. This permits a slight lateral movement of the key stems 47 in said slots 51, and enables ready adjustment of the operating plates 46 in relation to each other as the neighboring plates are actuated.

The arbitrary arrangement of the stacks of coins in the coin tray, in accordance with the denominational values thereof, has been previously outlined. It is, of course, essential that the combination bars 38 shall follow this arbitrary arrangement in order that, upon actuation of the respective combination bars, the proper coins may be paid out. Therefore, the arrangement of the mechanism previously described contemplates that the combination bar 38 which is nearest to the front of the machine, or that bar which is first, reading Fig. 1 of the drawings from left to right, will control the discharge of single pennies in that particular receptacle or chute 13 from which the pennies are discharged individually; the next two combination bars in the series each will control the discharge of double pennies; the fourth bar controls the nickels; the next two bars the two dime receptacles or chutes; the seventh combination bar controls the discharge of the quarters, and the last bar discharge of the half dollars. If we assume that sixty-one cents in change is to be paid out by the machine, the key bearing the symbol "61" will be depressed. The depression of this key and its operating plate 46

contacts with fingers on the bar 38 controlling the single penny discharge; also with one of the bars controlling discharge of the dimes, and likewise with the bar controlling discharge of the half dollars. That is to say, the contact fingers 44 on these several bars are in alignment with the operating plate 46 to which the key "61" is connected in order to produce the sixty-one cent combination, and this arrangement follows in connection with the remaining combination bars and the various operating plates 46 for the production of the various other combinations of change from one cent to ninety-nine cents.

At the front of the machine, and in position to receive the coins discharged from the several coin receptacles, is a chute 54 by which the discharged coins may be guided to a suitable collecting tray.

Associated with the several contact fingers 44 is a plurality of flexible guard fingers 55 which extend upwardly beyond the contact portions of said fingers. These guards prevent lateral displacement of the plates 46 from the fingers 44 and maintain the plates 46 in proper operative relation with the fingers 44.

It is also contemplated to employ with the herein-described machine locking mechanism for the coins within the several receptacles of the coin tray in order to make the machine most effective. Locking mechanism of the character covered by my pending application, Serial No. 343,710, filed December 10, 1919, is the most available for this purpose, and this mechanism is effectual to lock the machine under predetermined conditions, giving warning to the operator that a certain number of coins still remain in the trays, notwithstanding their locked condition, and permitting payments still to be made before the supply is wholly exhausted. It is unnecessary to disclose that locking mechanism herein, and reference is made to that application for a full understanding of such mechanism.

In the use of the herein-described machine the several coin receptacles 13 are supplied with the various denominations of the coins. When it is desired to pay out a certain amount of change the key 50 pertaining to the amount to be paid is depressed. As the operating plate 46 to which that key is connected is depressed it engages such of the contact fingers 44 as are necessary to effect operation of the several combination bars 38 for producing the particular change to be made, and these combination bars thereupon move downwardly. The descent of the combination bars causes the links 43 connected therewith to move downwardly, and this swings the rock shafts 34 to which said bars are connected with a resultant forward movement of the connecting arms 36. Thereupon

the coin ejector carriers 18 to which the connecting arms 36 are attached move forward, and the several coin ejectors 14 carried thereby are likewise projected into the 5 coin receptacles 13 and into engagement with the coins therein at the lower ends of the several stacks. As the ejectors move forwardly the lowermost coin or coins, as the case may be, are discharged, thus paying out the particular combination of change 10 which is made by the depression of the particular key which has been operated. On release of pressure from the key, the spring 53 associated therewith expands and moves 15 the operating plate 46 upwardly to its normal position. The spring or springs 26 of the coin ejecting mechanism which has been operated causes or cause the combination bar or bars to be moved upwardly, the expansion 20 of the spring or springs 26 moving the carrier or carriers 18 rearwardly and swinging the rock shafts 34 back to their normal position. This is the cycle of operations which is followed on the depression of each key 25 50, and in the operation of the parts there is freedom of movement, and likelihood of impairment is reduced to a minimum.

It will be observed that the mounting of the carriers 18 in suspended relation to the 30 support 31, through the medium of the hanger links 28, establishes a floating connection of these carriers with the crank arms 35 of the rock shafts 34, so that a flexible swinging movement exists in transmitting 35 power from these shafts to the carriers 38 for operating the coin ejectors 14. Furthermore, the change-combination-forming bars 38 occupy a floating relation with respect to the pivoted crank shafts 34, and freely 40 operate the same under depression of the operating plates 46. The floating character of the bars 38 is evidenced further by the fact that they have no positive connection with the plates 46 but are subject merely to 45 contact by the latter when depressed by the keys 47.

What I claim is:

1. A machine of the class described, comprising a plurality of coin receptacles, coin 50 ejecting mechanism associated therewith, a plurality of operating plates located in a plane above said coin ejecting mechanism, actuating keys associated with said plates, change-combination-forming bars located below said operating plates in transverse relation thereto and responsive to operating pressure applied to said keys, contact fingers included in said bars and spaced apart in accordance with the predetermined amount 55 of change to be formed thereby, whereby said bars are operable by predetermined operating plates the actuation of which produces the predetermined amount of change, and operating connections interposed between said bars and said coin ejecting mechanism for transmitting movement to the latter when said bars have been actuated by said operating plates.

2. A machine of the class described, comprising a plurality of coin receptacles, coin 70 ejecting mechanism associated therewith, a plurality of operating plates located in a plane above said coin ejecting mechanism, actuating keys associated with said plates, change-combination-forming bars located 75 below said operating plates in transverse relation thereto and responsive to operating pressure applied to said keys, contact fingers included in said bars and projecting upwardly therefrom, said fingers being spaced apart in accordance with the predetermined amount of change to be formed thereby, whereby said bars are operable by predetermined operating plates the actuation of which produces the predetermined amount of change, and operating connections interposed between said bars and said coin ejecting mechanism for transmitting movement to the latter when said bars have been actuated by said operating plates.

3. A machine of the class described, comprising a plurality of coin receptacles, coin ejecting mechanism associated therewith, a plurality of operating plates located in a plane above said coin ejecting mechanism, actuating keys associated with said plates, change-combination-forming bars located below said operating plates in transverse relation thereto and responsive to operating pressure applied to said keys, contact fingers included in said bars and projecting upwardly therefrom for engagement with the edges of said operating plates, spacing devices associated with said bars and interposed between said contact fingers to space the latter apart in accordance with the predetermined amount of change to be formed thereby, whereby said bars are operable by predetermined operating plates the actuation of which produces the predetermined amount of change, and operating connections interposed between said bars and said coin ejecting mechanism for transmitting movement to the latter when said bars have been actuated by said operating plates.

4. A machine of the class described, comprising a plurality of coin receptacles, coin ejecting mechanism associated therewith, a plurality of operating plates located in a plane above said coin ejecting mechanism, actuating keys associated with said plates, change-combination-forming bars located below said operating plates in transverse relation thereto and responsive to operating pressure applied to said keys, contact fingers included in said bars and projecting upwardly therefrom, said fingers being spaced apart in accordance with the predetermined amount of change to be formed thereby, whereby said bars are operable by predetermined operating plates the actuation of which produces the predetermined amount of change, and operating connections interposed between said bars and said coin ejecting mechanism for transmitting movement to the latter when said bars have been actuated by said operating plates.

5. A machine of the class described, comprising a plurality of coin receptacles, coin ejecting mechanism associated therewith, a plurality of operating plates located in a plane above said coin ejecting mechanism, actuating keys associated with said plates, change-combination-forming bars located below said operating plates in transverse relation thereto and responsive to operating pressure applied to said keys, contact fingers included in said bars and projecting upwardly therefrom, said fingers being spaced apart in accordance with the predetermined amount of change to be formed thereby, whereby said bars are operable by predetermined operating plates the actuation of which produces the predetermined amount of change, and operating connections interposed between said bars and said coin ejecting mechanism for transmitting movement to the latter when said bars have been actuated by said operating plates.

terminated operating plates the actuation of which produces the predetermined amount of change, guards associated with said contact fingers and extending beyond the contact portions thereof for maintaining operative relation of the operating plates with said fingers, and operating connections interposed between said bars and said coin ejecting mechanism for transmitting movement to the latter when said bars have been actuated by said operating plates.

5. A machine of the class described, comprising a plurality of coin receptacles, coin ejecting mechanism associated therewith, a plurality of operating plates located in a plane above said coin ejecting mechanism, actuating keys associated with said plates, change-combination-forming bars located below said operating plates in transverse relation thereto and responsive to operating pressure applied to said keys, contact fingers included in said bars and projecting upwardly therefrom, said fingers being spaced apart in accordance with the predetermined amount of change to be formed thereby, whereby said bars are operable by predetermined operating plates the actuation of which produces the predetermined amount of change, flexible guards associated with said contact fingers and extending beyond the contact portions thereof for maintaining operative relation of the operating plates with said fingers, and operating connections interposed between said bars and said coin ejecting mechanism for transmitting movement to the latter when said bars have been actuated by said operating plates.

6. A machine of the class described, comprising a plurality of coin receptacles, coin ejecting mechanism associated therewith, a plurality of operating plates, means for actuating the same, a plurality of change-combination-forming bars in juxtaposition to said operating plates and operable by the latter, a plurality of crank shafts to which said change-combination-forming bars are connected, and operating connections between said crank shafts and said coin ejecting mechanism for transmitting movement to the latter when said shafts have been actuated.

7. A machine of the class described, comprising a plurality of coin receptacles, coin ejecting mechanism associated therewith, a plurality of operating plates, means for actuating the same, a plurality of floating change-combination-forming bars in juxtaposition to said operating plates and operable by the latter, a plurality of crank shafts to which said change-combination-forming bars are connected, and operating connections between said crank shafts and said coin ejecting mechanism for transmitting movement to the latter when said shafts have been actuated.

8. A machine of the class described, comprising a plurality of coin receptacles, coin ejecting mechanism associated therewith, a plurality of crank shafts, connections between said crank shafts and said coin ejecting mechanism, a plurality of floating change-combination-forming bars arranged above said crank shafts and connected to the latter for actuating the same, and a plurality of operating plates arranged above said change-combination-forming bars for operating the latter when operating pressure is applied to said plates.

9. A machine of the class described, comprising a plurality of coin receptacles, coin ejecting mechanism associated therewith, a plurality of rock shafts, connections between said rock shafts and said coin ejecting mechanism, said rock shafts being provided with cranks, a plurality of floating change-combination-forming bars arranged above said crank shafts, links interposed between said bars and the cranks of said shafts for connecting the bars in operative relation to said shafts, and a plurality of operating plates arranged above said change-combination forming bars for operating the latter when operating pressure is applied to said plates.

10. A machine of the class described, comprising a plurality of coin receptacles, coin ejecting mechanism associated therewith, a plurality of rock shafts, connections between said rock shafts and said coin ejecting mechanism, said rock shafts being provided with cranks, a plurality of floating change-combination-forming bars arranged above said crank shafts, links interposed between said bars and the cranks of said shafts for connecting the bars in operative relation to said shafts, guide plates in which said change-combination-forming bars are slidably mounted, and a plurality of operating plates arranged above said change-combination-forming bars for operating the latter when operating pressure is applied to said plates.

11. A machine of the class described, comprising a plurality of coin receptacles, coin ejecting mechanism associated therewith, a plurality of rock shafts, connections between said rock shafts and said coin ejecting mechanism, said rock shafts being provided with cranks, a supporting member in which said rock shafts are journaled, a plurality of floating change-combination-forming bars arranged above said crank shafts, links interposed between said bars and the cranks of said shafts for connecting the bars in operative relation to said shafts, guide plates having a series of slots, said change-combination-forming bars being slidably mounted in the slots of said guide plates, a plurality of operating plates arranged above said change-combination-forming bars for operating the latter when operating pressure is applied to said plates, and means for

guiding said operating plates in relation to said change-combination-forming bars under applied operating pressure.

12. A machine of the class described, comprising a plurality of coin receptacles, coin ejecting mechanism associated therewith, a plurality of operating plates arranged in a plane above said coin ejecting mechanism, a supporting member located adjacent to the 10 coin ejecting mechanism, rock shafts journaled in said supporting member, guide plates suspended in a plane below said operating plates, said guide plates being slotted, a plurality of change-combination- 15 forming bars mounted in the slots of said guide plates and extending crosswise of the operating plates, connections between said change-combination-forming bars and said rock shafts, and connections between the 20 latter and the coin ejecting mechanism.

13. A machine of the class described, comprising a casing, a plurality of coin receptacles associated therewith, coin ejecting mechanism in association with said coin receptacles, a plurality of operating plates arranged in said casing in a plane above said coin ejecting mechanism, a guide plate in which said operating plates are slidably mounted, additional guide plates depending 25 from the first mentioned guide plate and provided with a plurality of slots, a plurality

of change-combination-forming bars slidably mounted in said slots, a plurality of rock shafts arranged below said change-combination-forming bars and connected to 35 the latter for operation thereby, and operating connections between said rock shafts and said coin ejecting mechanism.

14. A machine of the class described, comprising a casing, a plurality of coin receptacles associated therewith, coin ejecting mechanism in association with said coin receptacles, a plurality of operating plates arranged in said casing in a plane above said coin ejecting mechanism, a guide plate in 40 which said operating plates are slidably mounted, additional guide plates depending from the first mentioned guide plate and provided with a plurality of slots, a plurality of floating change-combination-forming bars slidably mounted in said slots, a plurality of rock shafts arranged below said change-combination-forming bars, the ends 45 of said rock shafts being provided with cranks, links interposed between said cranks and said change-combination-forming bars, and operating connections between said rock shafts and said coin ejecting mechanism. 50

In witness whereof I have hereunto subscribed by name.

EDWARD J. BRANDT.
